UNITED STATES PATENT OFFICE.

SOPHIA D. BRELSFOARD, OF MAROA, ILLINOIS.

COVER FOR TOOTH-BRUSHES.

1,209,111.

Specification of Letters Patent. Patented Dec. 19, 1916.

Application filed June 30, 1916. Serial No. 106,864.

To all whom it may concern:

Be it known that I, SOPHIA D. BRELSFOARD, a citizen of the United States, residing at Maroa, in the county of Macon, State 5 of Illinois, have invented certain new and useful Improvements in Covers for Tooth-Brushes; and I do hereby declare the following to be a full, clear, and exact description of the invention, such as will enable 10 others skilled in the art to which it appertains to make and use the same.

The present invention is directed to improvements in covers for tooth brushes, and has for its object to provide a device of this 15 character so constructed that the same can be easily and quickly engaged with or detached from the tooth brush, as desired.

A further object of the invention is to provide a cover of this character constructed 20 in such a manner that the tooth brush can be fully inclosed therein so as to protect the same from contamination.

A still further object of the invention is to provide a device of this character which 25 consists of a minimum number of parts so connected that they can be operated for removing or replacing the tooth brush in a quick and easy manner.

With these and other objects in view, this 30 invention resides in the novel features of construction, formation, combination and arrangement of parts to be hereinafter more fully described, claimed and illustrated in the accompanying drawing, in which—

35 Figure 1 is a side elevation of the device. Fig. 2 is a top plan view. Fig. 3 is a sectional view on line 3—3 of Fig. 2. Fig. 4 is an end view.

The cover consists of a pair of sections 1 40 and 2, said sections each consisting of a handle receiving portion 3 and brush head receiving portion 4, said sections being shaped so as to conform to the contour of the conventional make of tooth brush. The 45 sides of the portions 4 are provided with perforations 5 so that air can circulate through the sections when in confronting relation so as to permit the bristle of the brush to dry.

The outer ends of the portions 3 are provided with openings 6 which are adapted to be engaged by the inwardly directed extensions 7 carried by the arms of the U-shaped resilient clip 8, said clip serving to hold the portions 3 pivotally engaged, 55 whereby the sections 1 and 2 can be swung so that the tooth brush can be placed in the covering or removed therefrom. One of the head portions 3 is provided with a lug 9, while the other is provided with a spring 60 latch 10, said latch being adapted to engage the lug 9 so as to hold the sections 1 and 2 in confronting relation so as to entirely cover the tooth brush.

The sections 1 and 2 are preferably formed 65 from aluminum or any other suitable material may be employed, if desired.

From the foregoing description it will be seen that a covering of this character has been provided so constructed that a tooth 70 brush may be placed therein and thoroughly protected when being carried in a valise or in the pocket.

What is claimed is:—

A covering for tooth brushes comprising a 75 pair of complementary sections, each of said sections being provided with a handle receiving portion and a brush receiving portion, each handle receiving portion being provided with an opening at the end thereof, 80 a resilient U shaped clip engaging said openings, the sections being thereby pivoted to each other so that either section may be swung around said pivot as a center in a plane parallel to the longitudinal plane of 85 the other section, a spring latch carried by the end of one of the brush head receiving portions and a lug carried by the other brush head receiving portion for engagement by the latch as and for the purpose set forth. 90

In testimony whereof, I affix my signature, in the presence of two witnesses.

SOPHIA D. BRELSFOARD.
